UNITED STATES PATENT OFFICE.

CHARLES E. GREENLIEF, OF NEWTON, IOWA.

GEARING DEVICE FOR WRINGERS.

1,082,745.

Specification of Letters Patent. Patented Dec. 30, 1913.

Application filed June 14, 1912. Serial No. 703,711.

To all whom it may concern:

Be it known that I, CHARLES E. GREENLIEF, a citizen of the United States, residing at Newton, in the county of Jasper and 5 State of Iowa, have invented a new and useful Gearing Device for Wringer, of which the following is a specification.

My invention relates to that class of washing machines in which both the machine and 10 wringer are operated by power.

The object of my invention is to provide a gearing device for wringers, of the class mentioned, whereby the wringer may be detachably mounted on a machine in position 15 for wringing clothes into or out of the tub, and whereby the wringer may, at the option of the operator, be detachably mounted on the machine in such position that clothes may be wrung from one receptacle 20 to another, the second position of the wringer being such that it stands away from the tub, it being my purpose to provide such an attachment whereby the wringer may be in gear in either position of its movement.

25 A further object is to provide means whereby a wringer may be detachably mounted on a washing machine in gear with a shaft operated by any suitable motive power and from which the wringer may be 30 detached without the use of tools, pins, bolts or the like.

My invention consists in certain details, in the construction, arrangement and combination of the various parts of my device, 35 whereby the objects contemplated are attained, as hereinafter more fully set forth, pointed out in my claims, and illustrated in the accompanying drawings, in which—

Figure 1 shows a front elevation of a 40 washing machine with a wringer mounted thereon by means of my improved attachment. Fig. 2 shows a detail view, partly in section of part of the washing machine and wringer and of my attachment, the 45 wringer being in its position away from the tub. Fig. 3 shows a top or plan view of part of a washing machine tub with my improved attachment installed thereon.

In the accompanying drawings I have 50 used the reference numeral 10 to indicate an ordinary washing machine tub, mounted on legs 11. Suitably mounted beneath the body of the tub is a power shaft 12 on which is a

belt wheel 13 designed to be operated from any suitable source of power. Beneath the 55 tub body and suitably supported, is a gear casing 14 in which is mechanism, not shown, of any suitable kind whereby the shaft 15 may be operated from the shaft 12, and may be thrown into or out of gear and also 60 whereby the shaft 16 may be thrown out of gear, into gear, or reversed. On the shaft 15 is a disk wheel 17 to which is pivotally secured, at a point off center, a pitman 18. Pivoted to the pitman 18 is a lever 19 centrally pivoted on a bracket 20 mounted on the tub body. Pivoted to the upper end of the lever 19 is a pitman 21 from which alternating rotary motion is imparted to the 65 dolly shaft by suitable mechanism, not 70 shown. The levers 22, 23 and 24 operate the mechanism, not shown, within the gear casing 14. Connected with that mechanism and extending to a position beneath the edge of the tub is the shaft 16, already mentioned, 75 on the end of which is a beveled gear 24. Rotatably mounted in suitable bearings is 80 an upwardly extending shaft 25 on the lower end of which is a beveled gear 26 in mesh with the beveled gear 24. The gears 24 and 26 are received within the gear casing 27. Mounted on the upper portion of the tub body is a bracket 28 extending away from the tub body and provided with the supporting brace 29 which extends downwardly 85 and is suitably mounted at its lower end. Formed on the bracket 28 is an upwardly extending bearing 30 designed to receive a vertical shaft 31 which is connected at its lower end with the upper end of the shaft 90 35 by means of a universal joint 36. On the upper end of the shaft 31 is a beveled gear 37.

I have used the reference numeral 38 to indicate generally a wringer which has the 95 wringer shaft 39, on the end of which is a beveled, vertical gear 40. On the bracket 28 are upwardly extending angular lugs 41 and 42. Formed on the wringer frame is a bracket 43 in the lower surface of which is 100 an angular socket 44 designed to receive either of the lugs 41 or 42. The lugs 41 and 42 are so constructed and arranged and the socket 44 is so constructed that when the lug 41 is received in the socket 44, the 105 wringer 38 is in position extending across

2
the upper portion of the tub at one side thereof, where clothes may be conveniently wrung into the tub or out of the tub and with the beveled gear 40 in mesh with the 5 beveled gear 47. When the lug 42 is received in the socket 44, the wringer 48 stands in position extending away from the tub so that clothes may be wrung through it from one receptacle into another. When the 10 wringer is in its last described position, it is far enough away from the tub so that the tub does not interfere with its operation. When the wringer is in its last named position, the beveled gear 40 is in mesh with the 15 beveled gear 37.

In the practical operation of a wringer and washing machine equipped with my improved gearing, the wringer may be placed in position across the upper part of 20 the tub and clothes may be wrung from the tub or into it and the wringer may be operated in either direction or thrown out of gear. If it is desired to use the wringer away from the tub it may be wholly detached and placed in position with the lug 25 42 received in the socket 44 and may then be operated by the power which runs the machine without being interfered with in any way by the machine tub.

30 A great many variations may be made in the details of construction of my device without departing from its essential features.

The advantages of my improved attachment are numerous. It provides means for 35 mounting a shaft and also means whereby the wringer may be used for wringing clothes from the tub or for wringing clothes from one receptacle to another. In either 40 of its positions, the wringer is in gear with the shaft in the bearing formed on the attachment and may be operated by the power which runs the machine. A special advantage is found in the complete detachability 45 of the wringer. The wringer may be removed from the machine without the use of tools and without the removal of screws, bolts or pins. There are no small detachable parts to be lost when the wringer is 50 moved. The wringer may be placed inside the tub for storage or transportation and the trouble and expense of packing or crating the washing machine are greatly reduced. With ordinary power washing 55 machines, tools are required to remove the wringer and the wringer is mounted on the machine by means of bolts, screws or the like which are likely to be lost or misplaced when the wringer is removed. It is readily 60 seen that considerable time is saved where the wringer is easily detached by simply lifting it upwardly as may be done with my improved attachment.

65 Washing machines of this class are comparatively heavy and the removability of

the wringer reduces the weight to a considerable extent when the operator desires to move the machine from place to place.

In the following claims, by the terms "body" or "body portion", I mean a tub or the like; by the term "frame", I mean the wringer or the like and by the word "detachable" I mean detachable without the use of tools or the removal of screws, bolts or the like.

75 What I claim is:

1. In a device of the class described, the combination of a body, a shaft at one side thereof, a frame, detachable coacting supporting means on said body and on said frame, whereby the frame may be mounted on the body, a shaft in said frame, and gearing devices for operatively connecting said shafts when the frame is mounted on the body.

80 2. In a device of the class described, a body, an upright shaft at one side thereof, a bracket secured to said body adjacent to said shaft, a frame, detachable coacting supporting means on the frame and on the body whereby the frame may be mounted on the body, a horizontal shaft in the frame, and gearing devices for operatively connecting said shafts, when the frame is in position.

85 3. In a device of the class described, the combination of a body, a shaft at one side thereof, a frame, detachable coacting supporting means on said body and on said frame, whereby the frame may be mounted on the body, in different positions, a shaft in said frame, and gearing devices for operatively connecting said shafts when the frame is mounted on the body, in either of its positions.

95 100 4. In a device of the class described, the combination of a body, a bracket mounted on said body, having a bearing formed thereon, a shaft mounted in said bearing, a frame, detachable coacting supporting means on said frame and on said bracket, for supporting said frame on said body in different positions, a shaft in said frame and gearing devices for operatively connecting said shafts when the frame is in either 105 of its positions.

110 5. In a device of the class described, a body, a bracket having a bearing formed thereon, secured to said body, a shaft mounted in said bearing, a beveled gear thereon, a frame, a shaft mounted therein, a beveled gear on said last named shaft, coacting supporting means on said frame and on said bracket, whereby said frame may be detachably mounted on said body, in different positions, with said beveled gears in mesh with each other in either position of the frame.

115 120 125 130 6. In a device of the class described, a body, a bracket having a bearing formed

thereon, secured to said body, a shaft mounted in said bearing, a beveled gear thereon, a frame, a shaft mounted therein, a beveled gear on said last named shaft, co-acting supporting means on said frame and on said bracket, for detachably mounting said frame on said body, in different positions, with said beveled gears in mesh with each other in either position of the frame, said means being so shaped as to prevent movement of said frame in any direction.

Des Moines, Iowa, May 31, 1912.

CHARLES E. GREENLIEF.
